ARROW TAIL FEATHER

Francis W. Melton, 1306 47th St.,
Des Moines, Iowa 50310

Filed May 10, 1973, Ser. No. 359,098

Term of patent 14 years

Int. Cl. D22—05

U.S. Cl. D22—12

FIG. 1

FIG. 2

FIG. 3

FIG. 4

FIG. 5

FIG. 6

FIG. 1 is a side elevational view of an arrow tail feather showing my new design;

FIG. 2 is a top view;

FIG. 3 is a bottom view;

FIG. 4 is an enlarged end elevational view looking toward the left in FIG. 1;

FIG. 5 is a side elevational view of a modified form of the arrow tail feather wherein the openings therein are reduced in size and increased in number; and

FIG. 6 is a side elevational view of another modified form of the arrow tail feather wherein the openings therein are reduced in size, increased in number and extended laterally of the tail feather.

I claim:

The ornamental design for an arrow tail feather, substantially as shown and described.
